UNITED STATES PATENT OFFICE.

BRYANT D. CAMPBELL, OF OAKLAND, CALIFORNIA.

TELEPHONE SYSTEM.

1,382,891.

Specification of Letters Patent. Patented June 28, 1921.

Application filed February 6, 1917. Serial No. 146,982.

To all whom it may concern:

Be it known that I, BRYANT D. CAMPBELL, citizen of the United States, residing at Oakland, in the county of Alameda and 5 State of California, have invented certain new and useful Improvements in Telephone Systems, of which the following is a specification.

This invention relates to coin operated 10 telephone systems and comprises automatic means for registering and counting every coin collected when the coin performs its function in establishing a connection between two telephones in the system.

15 The invention is illustrated in the accompanying drawings which form a part of this specification and the appended claims.

Referring to the drawings:

Figure 1 is a diagram of a circuit of the 20 system including two telephones, the circuit and coin mechanism being shown in normal condition.

Figure 2 is a diagram of said circuit showing the transmitter of the calling telephone "dead" and the bell circuit closed 25 and ringing the bell of the other telephone.

Fig. 3 is a diagram of said circuit in normal condition, after the condition in Fig. 2 has ceased, with the exception that the 30 transmitter of the calling telephone is "dead."

Fig. 4 is a diagram of said circuit in the condition shown in Fig. 3 and also with the receiver of the calling telephone off the 35 hook and the coin operating and registering mechanism of said telephone in position holding the coin, which coin is yet to be registered.

Fig. 5 is a diagram of the circuit brought 40 back to its normal condition, the coin having been ejected, after the condition shown in Fig. 4 when the party called fails to answer.

Fig. 6 is a diagram of the circuit in the 45 condition as shown in Fig. 4 except with the called telephone receiver off the hook.

Fig. 7 is a diagram of the circuit in the condition as shown in Fig. 4 and with the called telephone speaking and in such condition that the calling party can hear the 50 called party but can not speak to him.

Fig. 8 is a diagram of the circuit in the condition shown in Fig. 7 and in the act of 55 registering the coin and depositing it in the coin box.

Fig. 9 is a diagram of the circuit after the coin has been registered and deposited and with both telephones in talking condition.

Fig. 10 is a diagram of the circuit when 60 the parties have ceased talking and placed the receivers back on their hooks, which condition is the normal condition as shown in Fig. 1.

Fig. 11 is a side elevation of the coin 65 mechanism of the telephone system, the casing of said mechanism being shown in section.

Fig. 12 is a plan of said mechanism.

Fig. 13 is a view in elevation of the coin 70 mechanism, with certain parts thereof removed, showing the interior operating parts, the casing being shown in section.

Fig. 14 is a sectional view of the coin mechanism taken on line X—X of Fig. 13. 75

Fig. 15 is a view of a telephone receiver switch for closing a circuit which operates the coin mechanism to return the coin to the called party when the called party fails to answer. 80

Fig. 16 is a fragmentary side view of the coin operated switch for effecting the establishment of complete talking connection between two telephone stations.

Referring to Figs. 1 to 10 inclusive A and 85 B represent two telephone stations which are included in the circuit indicated C of an automatic telephone system. Included in the circuit of the system at each station is one of my coin operating and registering 90 mechanisms generally indicated D.

The coin operating and registering mechanism may be described as follows:

Numeral 1 indicates a frame upon which the various parts of the mechanism are 95 mounted. Within said frame is located a coin chute 2, extending downwardly from the top of the frame. A bracket 3 extends outwardly from one side wall of the chute, in which a coin arresting lever 4 is pivoted 100 at 5. A pin 6 extends inwardly from said lever and is adapted to be projected through an aperture 7 in the side wall of the chute in the path of the coin as will be described hereinafter. A spring 8 is adjustably 105 clamped at its upper end on a threaded pin 9, extending from the frame, between two thumb nuts 10 and 11, the lower end of which spring engages the coin arresting lever at one side of its pivot and normally 110

maintains the lever in position with the pin 6 withdrawn from the chute. A magnet 12 is mounted adjacent the end of the lever 4 at the side of the pivot opposite the spring 8, on a bracket 13, extending outwardly from the frame, which magnet when energized swings the lever 4 and introduces the pin 6 through slot 7 into the chute 2 in the path of the coin which pin is adapted to arrest the coin in the chute adjacent an opening 15 in wall 16 of said chute as shown in dotted lines in Fig. 13.

A coin-actuating lever 20 is pivoted at 21 to the frame 1 at one side of the chute and has a pair of pins 22 projecting from its lower end through slots 23 in the side wall of the chute. A spring 25 secured at 26 to the frame 1 engages the lower portion of the lever 20 and normally maintains said lever in position with the pins 22 at the ends of the slots 23 at the side of the chute, opposite opening 15, in which position said pins rest adjacent the edge of the coin arrested by the pin 6 as shown in Fig. 13. The lever 20 has a finger hook 30 extending outwardly therefrom through a slot 31 in a casing 35 which incloses the frame 1 and the parts therein. The casing 35 is provided with a slot 36 which registers with the upper end of chute 2 through which a coin may be introduced into the upper end of said chute. The opening 15 of chute 2 leads into the upper end of a chute 37, the lower end of which opens into a coin drawer 38 in the bottom of the casing 1.

A coin-actuated register lever 40 is pivoted at 41 with its forward arm extending to the opening 15 of chute 2 and resting directly above the upper end of chute 37. To the rear arm of said lever is connected the upper end of link 42, the lower end of which is connected to the operating arm 43 of a coin register 45. A spring 46 secured to the frame 1 engages the upper side of the lever 40 and holds said lever and the register operating arm and mechanism in their initial position to be operated by the coin as will be hereinafter described. A threaded pin 48 extends outwardly from the rear arm of lever 40 through a slot 49 in one side wall of the chute 2, on which pin a finger 50 of insulation is clamped between two nuts 51 and 52 which screw on said pin, which finger is adapted to engage a cam surface 53 on the upper end of a spring contact 55 and press the upper end of said contact into contact with the frame 1 to close an electric circuit hereinafter described. The chute 2 is provided with a side opening 56 at its lower end which communicates with an outlet 57 in the side wall of the casing 35 which outlet opens into a coin delivery receptacle 60, and the bottom wall 61 of the chute inclines downwardly to said receptacle so as to allow a coin released from the pin 6 to roll out of

the chute through said opening and outlet into the delivery receptacle as will be hereinafter described.

Means are provided for returning the coin, dropped by the calling party into the coin operating and registering mechanism at the calling station to said party, when the party at the called station fails to answer. Said means includes a switch E Fig. 15 which comprises a jointed arm 62 depending from the receiver hook of each telephone station and a pair of spring contacts 63 and 64 secured to the telephone standard on which the receiver hook is fulcrumed. Said arm 62 comprises a stationary member 65 secured to the receiver hook and a hinged member 66 which is hinged at 67 to the stationary member 65. Said hinge permits the arm 66 to swing and drag over contact 63 so as not to depress said contact into contact with contact 64, when the receiver is taken off the hook and the hook swings up. Said arm members have shoulders 68 and 69 adapted to engage and hold the arm members rigid in alinement so that when the receiver is replaced upon the hook and the hook swung down, the arm member 66 will engage and momentarily depress contact 63 into contact with contact 64 and momentarily close the coin ejecting circuit as will be hereinafter described.

The operation of my invention is as follows:

Assume the two stations A and B of the system to be in normal condition indicated in Fig. 1 and a person at station A desires to speak to a person at station B.

The person at station A closes switch 70 at said station and establishes an electric circuit from battery 75, through lead 76, switch 70, lead 77, magnet 78 and lead 79 back to battery, energizing magnet 78 which closes switch 80 and "opens" the circuit of transmitter 71 of station A, whereupon an electric circuit is established from battery 75 through lead 81, switch 80, lead 82, switch 70, lead 83, through the receiver switch 84, of station B, lead 85, bell 86 of station B, lead 87 back to battery, ringing bell 86 of station B, as indicated in heavy lines in Fig. 2. The person at station A then releases switch 70 and breaks said circuits, whereupon bell 86 ceases ringing but switch 80 remains closed and transmitter 71 of station A remains dead. The calling party at station A then removes the receiver 90 of said station off its hook and closes the receiver switch 91 of said station, which establishes an electric circuit from battery 75, through lead 81, switch 80, leads 82 and 92, receiver switch 91, lead 93, magnet 12, and leads 94 and 87 back to battery, and energizes magnet which swings lever 4 and projects pin 6 into the chute 2 which arrests a coin 100 deposited in the slot, as shown in Fig. 13, which

condition is illustrated in heavy lines in Fig. 4, during which condition the transmitter of telephone station A still remains "dead."

5 When the called party at station B fails to answer and the calling party at station A hangs up receiver 90, the switch arm 66 of said receiver engages and momentarily depresses contact 63 into contact with contact 64 and momentarily closes and establishes the coin returning circuit from battery 75, through leads 81 and 101, switch E, leads 102 and 103, magnet 105, and leads 106 and 87, back to battery 75, thus energizing magnet 105 which opens switch 80 and breaks the circuit controlling the coin mechanism D, and deenergizes coin mechanism magnet 12, whereupon spring 8 swings the pin end of lever 4 outwardly and withdraws the pin 6 from under the coin 100, allowing the coin to drop and roll along the bottom 61 of the chute out through opening 56 and outlet 57 into the coin delivery receptacle so that the calling party may take it back. This condition is shown in Fig. 5.

When the called party takes the receiver 110 at the called station off the hook to answer the calling party at station A, as shown in Fig. 6, receiver switch 111 is closed, which establishes a circuit from battery 75 through lead 87, battery 115, lead 116, switch 120, lead 121, transmitter 125 of station B, lead 126, receiver 110, lead 127, receiver switch 111, lead 83, lead 128, receiver switch 130 of station A, lead 131, receiver 90 of station A, leads 136 and 137, lead 82, switch 80, lead 81 back to battery 75, in which condition the party at B station may talk to party at A station, but the coin at station A has not yet been collected and registered and the transmitter of station A is still "dead" so that the party at station A cannot yet speak to the party at station B, but can hear said party, which condition is represented in heavy lines in Fig. 7, during which condition the called party at station B answers the calling party at station A.

When the calling party at station A hears the answering party at station B, the calling party places his finger on hook 30 of the coin operating and registering mechanism at station A, depresses said hook and swings lever 20 on its pivot, so that the lever pins 22 engage the rear edge of coin 100 and force it backwardly through chute slot 15 between the lower end 140 of said slot and the forward arm of coin register operating lever 41, swinging said lever on its pivot out of the way until the coin passes into chute 37 through which it drops into and is collected by the coin drawer 38 during which operation of the lever 40, the register 45 is operated through link 42 and arm 43 and the coin is registered by the register, while the arm 50 engages cam 53 and presses switch

55 into contact with frame 1, which momentarily establishes a circuit from battery 75, through leads 81 and 101, lead 145, to frame 1 and through switch 55, then through lead 146, lead 103, magnet 105, leads 106 and 87 back to battery 75, as shown in Fig. 8, thus momentarily energizing magnet 105 and throwing switch 80 to the left, which breaks the circuit including magnet 12, withdrawing pin 6 from chute 2, and establishes a circuit from battery 75, through lead 81, switch 80, lead 150, transmitter 71 of station A, lead 136, receiver 90 of station A, lead 131, a receiver switch 130 of station A, leads 128 and 83, receiver switch 111 of station B, lead 127, receiver 110 of station B, lead 126, transmitter 125 of station B, lead 121, switch 120, lead 116, battery 115, lead 87 back to battery 75, whereby the complete connection between stations A and B is made so that the parties at both stations may talk to and hear each other, which condition is shown in Fig. 9.

When the parties cease talking to each other and hang up the receivers 90 and 110, the circuit including the two stations A and B is broken and the normal condition is again established as shown in Fig. 10.

Having described my invention, I claim as new and desire to secure by Letters Patent:

1. In a coin-controlled telephone, a coin-controlling mechanism provided with a coin chute normally open so that a coin will pass therethrough and out of said mechanism, a pin, a magnet included in the receiver circuit for projecting said pin into said chute to arrest a coin deposited therein, and means whereby the calling party may actuate said mechanism to collect the coin when he hears the called party.

2. In a coin-controlled telephone system, coin-controlled means operable entirely by the calling party for completing a connection and for collecting the coin when the called party answers, and for returning the coin when the called party fails to answer.

3. In a coin-controlled telephone system, coin-controlled means operable entirely by the calling party for completing a connection and for collecting the coin when the called party answers, and register operable by said coin-controlled means for registering the collected coin.

4. In a coin-controlled telephone system, a register, a register operating lever, means connecting said operating lever with the register mechanism, means operable entirely by the calling party for collecting the coin when the coin has completed a connection in the system, said lever being adapted to engage said coin and to operate said register and register the coin when the coin is collected.

5. In a coin-controlled telephone system, a register, and coin-controlled means operat-

able entirely by the calling party engaged by the coin for operating said register and registering the coin when the connection between two stations has been effected by the 5 coin and the coin is collected, and for returning the coin to the calling party when the called party fails to answer.

6. In a telephone system, a coin means operatable entirely by the calling party for 10 completing a connection between two telephones in the system, and for returning the coin to the calling party upon failing to establish a connection.

7. In a coin-controlled telephone, a coin 15 controlling mechanism provided with a coin chute normally open so that a coin will pass therethrough and out of said mechanism, said chute being provided with an opening in its wall, a pin mounted to project into said 20 chute below said opening, a magnet included in the receiver circuit for projecting said pin into said chute to arrest a coin deposited therein, a coin box, and an actuating lever for engaging and forcing the coin in the 25 chute through said opening from which the coin drops in said coin box.

8. In a coin-controlled telephone, a coin 30 controlling mechanism provided with a coin chute normally open so that a coin will pass therethrough and out of said mechanism, a pin, a magnet included in the receiving circuit for projecting said pin into said chute to arrest a coin deposited therein, a coin register, a lever for actuating said register, a 35 coin box, and means for forcing the arrested coin out of the chute into engagement with said lever to actuate the register and into the coin box.

9. In a telephone system, a coin means

operatable entirely by the calling party for 40 completing a connection between two telephones in the system, for collecting the coin after the connection has been made and for returning the coin to the calling party in case the connection is not made. 45

10. In a coin-controlled telephone system, a coin means operatable entirely by the calling party for completing connection between two telephone stations, and for automatically returning the coin in case of failure to 50 get a party.

11. In a coin-controlled telephone system, coin-controlled means operatable entirely by the calling party for completing a connection and for collecting the coin when the called 55 party answers, and for returning the coin when the called party fails to answer, and a register operatable by said coin-controlled means for registering the collected coin.

12. In a coin-controlled telephone, a coin 60 controlling mechanism provided with a coin chute normally open so that a coin will pass therethrough and out of said mechanism, a pin mounted to be projected into said chute, means in the receiver circuit for shortening 65 out the transmitter of the calling party when said party takes the receiver off the hook, a magnet included in the receiver circuit for projecting said pin into said chute to arrest a coin dropped therein, means whereby the 70 calling party may actuate said mechanism to collect the arrested coin when he hears the called party, and a switch closed by said actuating means for establishing the transmitter circuit when the coin is collected. 75

In testimony whereof I affix my signature.

BRYANT D. CAMPBELL.
